UNITED STATES PATENT OFFICE

2,076,338

RAILWAY CROSSING

John J. Greely, Maysville, Ky.

Application July 23, 1935, Serial No. 32,789

1 Claim. (Cl. 238—8)

My invention relates generally to means utilized in providing smooth passage over railway tracks of vehicle and pedestrian traffic, and particularly to a railway crossing of this type which is bodily removable and replaceable, and an important object of the invention is to provide a railway crossing of this character which is capable of efficiently taking the place of permanent constructions now generally in use.

Another important object of my invention is to provide a relatively inexpensive crossing of the character indicated which is bodily removable and replaceable for repair purposes or for replacement of elements thereof, and which permits elimination of the masonry and other expensive constructions which are expensive to repair and frequently must be replaced entirely at great cost if seriously impaired through accident or wear.

Other important objects of my invention will be apparent from a reading of the following description in connection with the drawings, wherein for purposes of illustration I have shown a preferred embodiment of my invention.

In the drawings:—

Figure 1 is a top plan view of an embodiment of the invention.

Figure 2 is a transverse vertical sectional view taken through Figure 1.

Figure 3 is a bottom plan view of one of the plates.

Figure 4 is a transverse vertical sectional view taken through the laterally outward end of one of the central plates.

Figure 5 is a plan view of one of the stay-rod clamps.

Referring in detail to the drawings, the numerals 4 refer generally to the railway ties upon which the rails 5 and 6 are laid in conventional manner, the said rails having the outer base flanges 7 and the inner base flanges 8.

In accordance with the present invention there is mounted at each end of the ties and spaced therefrom masonry retaining walls about as long as the width of the crossing contemplated, each formed in its top and its inner side with the notch which provides the shoulders 12.

Laid in place between the retaining walls 10 and 11 and the outer sides of the respective rails 5 and 6 are the outer plates 13, 14, and between the rails 5 and 6 the central plates 15 and 16.

Each outer plate 13, 14 is a generally rectangular body of pressed steel, cast iron, or other suitable material which has an inwardly inclining upper surface, which upper surface is provided with suitable roughening or anti-skid for-

mations as the builder may require. From the top 17 depend the side flanges 18 which have parallel thereto ribs or other reinforcing arrangements at the option of the builder, and the outer end is squared to rest on the shoulder 12 of the respective retaining wall and the inner end of the respective outer plates 13, 14 is cut away at the upper part as indicated by the numeral 19 to provide proper clearance with the head 20 of the rail to define a shoulder 21 which engages the web of the rail, the underside of the rail head 20, and to rest upon the base flange 7, as clearly indicated in Figure 2.

The similar central plates 15 and 16 are generally rectangular in form and include the top 22 from which depend the side flanges 23 and the outer end flanges 24 which have the angulated part 25 which rests directly upon the inner base flange of the rail, as exemplified in Figure 4. The end wall 24 rests against the web of the rail and its upper end engages the underside of the head of the rail. The side flanges 23 which connect the opposite ends of the end wall 24 are cut away as indicated by the numeral 26 to provide proper clearance with the head of the rail to accommodate the flange on the car-wheels of the rolling stock which travels on the rails 5 and 6.

The central plates 15 and 16 are tapering as indicated in Figure 2 and their inner end walls are provided with registering semi-circular grooves 27 which register when the central plates 15 and 16 are dropped into place, and form a circular bore receiving the round rod 28 which locks these plates relative to each other and makes their tops level.

The central plates have ribs 29 on their underside for reinforcing purposes, but any other suitable reinforcing formation may be utilized if desired. The outer end walls of the plates 15 and 16 are recessed as indicated by the numeral 30 to provide proper clearance with the rail joint bolts 31, and the outer plates 13 and 14 are similarly recessed to accommodate the opposite side of the rail joints as indicated in dotted lines at 32 in Figure 1.

The formations described bring the tops of the various plates approximately on the same level or on a level with the tops of the heads of the rails, which are at an elevation with respect to the tops of the retaining walls 10 which are flush with the ground level or vehicle roadway which is generally designated 33.

For preventing spreading of the rails at the crossing extra stay-rods 34 and 35 are provided which have thereon clamps 36 which are trav-

55

ersed by the ends of the stay-rods and are clamped in place on the base flange of the rails as shown in Figure 2 by nuts 37 on the outwardly projecting ends of the stay-rods.

5 It is obvious that the outer plates 13 and 14 may be lifted out of place and replaced with new plates when wear or accident impairs the outer plates, and that the replacement plates may be simply dropped into place in the positions indicated in the drawings.

10 It is further to be noted that upon withdrawal of the locking bar or rod 28 the inner ends of the central plates 15 and 16 may be separated and the central plates simply lifted out of place and replaced by new central plates when desired. It is obvious that after the central plates 15 and 16 15 have been put into position, the rod 28 is slid into place in the grooves 27 when the tops of the central plates have been brought flush with each other.

15 Although I have shown and described herein a preferred embodiment of my invention, it is to

be definitely understood that I do not desire to limit the application of the invention thereto, and any change or changes may be made in the materials, and in the structure and arrangement of the parts, within the spirit of the invention and 5 the scope of the subjoined claim.

What is claimed is:—

10 In combination, a railroad track including a pair of rails, a connecting member between the bases of said rails to prevent spreading of the rails, a pair of load crossing plates between the rails at the said connecting member, said plates abutting each other at their inner edges, and abutting the rails at their edges opposite to the abutting edges, said plates being disposed in inclined arched positions with their high point 15 where the plates abut each other, a groove in the abutting inner vertical surfaces of the plates and a rod seated in said groove to maintain the abutting edges of the plate in fixed relative position.

15 JOHN J. GREELY.
